(57) **CLAIM**

The ornamental design for an electronic device with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of an electronic device with graphical user interface showing the claimed design;

FIG. 2 is a rear view thereof;

FIG. 3 is a right side view thereof;

FIG. 4 is a left side view thereof;

(Continued)

FIG. 5 is a top view thereof; and,
FIG. 6 is a bottom view thereof.

The broken lines in the figures show portions of the wearable electronic device with graphical user interface that form no part of the claimed design.

UNITED STATES PATENT AND TRADEMARK OFFICE
CERTIFICATE OF CORRECTION

PATENT NO. : D873,680 S
APPLICATION NO. : 29/640648
DATED : January 28, 2020
INVENTOR(S) : Akana et al.

Page 1 of 1

It is certified that error appears in the above-identified patent and that said Letters Patent is hereby corrected as shown below:

In the Description, item (57), page 2, Column 1, Lines 3-5 replace:
“The broken lines in the figures show portions of the wearable electronic device with
graphical user interface that form no part of the claimed design.”

With:

--The broken lines in the figures show portions of the electronic device with
graphical user interface that form no part of the claimed design--

Signed and Sealed this
Twenty-first Day of April, 2020
